JOHN F. ROGERS, OF CLEVELAND HEIGHTS, OHIO, ASSIGNOR TO THE WELLMAN ENGINEERING COMPANY, OF CLEVELAND, OHIO, A CORPORATION OF OHIO

FEED MECHANISM FOR GAS PRODUCERS

Application filed August 1, 1927. Serial No. 209,769.

This invention relates to improvements in feed mechanisms such for example as fuel feeders for gas producers and the like, that is, mechanisms for feeding fuel at a regular stated rate onto the bed of fuel in the producer body, while preventing the escape of gas. The present invention is in certain respects an improvement over the construction disclosed in my copending application, Serial Number 27,379, filed May 2, 1925.

In one type of apparatus disclosed in the aforesaid application, two valves are arranged at spaced intervals in the line of feed of the fuel and the operation of these valves one at a time intermittently is brought about by a cam which is rotated with a step by step motion. The complete rotation of the cam, of course, represents one full cycle, that is, the opening and closing of one valve and the later opening and closing of the other valve. Consequently, that portion of the cam which lowers and raises the valves is necessarily rather small in angular dimensions and the lifting and descent sides are rather steep. Each valve is held closed by a weight and this weight must be moved by the cam. As the follower moves down from the high spot of the cam on the descent side thereof, the tendency of the weight is to move the cam ahead and thus close the valve sooner than is desired. In order to overcome this tendency special pawl mechanisms have been resorted to.

One of the objects of the present invention is the provision of means for balancing the action of the cam drive for feeders of the type described to prevent such overrunning of the cam.

Another object is the provision of means for causing a balancing weight not only to prevent overrunning of the cam as the valve weights descend but also to assist the cam in raising the valve weights when the valves are opened. In this manner the power required to lift the balancing weight is reduced.

A further object of the invention is the provision of means for effectively closing at all times the opening in the feed chamber through which the valve operating lever extends.

Still another object is the provision of means for permitting the renewal of valve seat members without the necessity of tearing down the entire feeding apparatus.

Other objects and features of novelty will appear as I proceed with the description of that embodiment of the invention which, for the purposes of the present application, I have illustrated in the accompanying drawings, in which

Fig. 1 is a side elevation of a fuel feeding apparatus embodying my invention;

Fig. 2 is a vertical sectional view of the same;

Fig. 3 is a side elevation looking in the direction of arrow, Fig. 1;

Fig. 4 is a perspective view of the double cam and triple follower mechanism employed in carrying out the invention; and

Fig. 5 is a vertical sectional view taken substantially on the line 5—5, Fig. 1, showing means for freeing the valve-seat members.

Similar reference characters refer to like parts throughout the views.

In the drawings, the fuel feeding apparatus is provided with a base 10 which is designed to be secured to the cover of a gas producer over an opening in the same. Such cover and the producer body are generally relatively rotatable so that the fuel as fed down by the feeding apparatus may be distributed over the fuel bed. The base member 10 is preferably integral with a casing section 11. Above the section 11 and secured thereto by bolts 12 is a second casing section 13, while a third section 14 is supported upon the section 13 and secured thereto by bolts 15.

The section 11 is provided with removable plates 16 through which access to the casing may be had for inspection or repair. Similar removable plates 17 and 18 are provided for the sections 13 and 14, respectively. A shield 19 is movable vertically behind pins 8, which are mounted in base 10. Behind this shield the casing is provided with a horizontal slot 20. The latter is sealed normally with sand. When it becomes desirable to shut off the feeding apparatus from the producer body, as when repairs are to be made,

the shield 19 is lifted and a plate, indicated at 21 by dotted lines in Fig. 2, may be slid over the opening in the base member 10 through slot 20 and a corresponding slot (not shown) in the shield 19. As a means for cooling the casing section 11 and the valve seat above it, an open chamber 22 may be provided for the reception of cooling water.

Between the sections 11 and 13 and also between the sections 13 and 14 are located valve seat members 23 and 24 which are flat heavy plates that may be slid into or out of operative position after bolts 12 and 15 have been removed. Set screws *a*, Figs. 1 and 5, are threadably mounted in laterally projecting portions of the casing sections 13 and 14 and are adapted to engage portions of the sections next below. When these set screws are turned down the spaces occupied by the plates 23 and 24 are enlarged. These plates may then be taken out and new ones inserted. The plates 23 and 24 have circular openings along the periphery of which are formed valve seats 25 and 26, respectively. The casing members 13 and 14 are each shaped at their lower ends like hoppers so as to direct the descending fuel into the openings bounded by the valve seats 25 and 26.

Cooperating with the valve seats 25 and 26 are valve members in the form of bells 27 and 28. These bells have integral perforated suspending lugs 29 through which extend pins 30, the ends of the pins resting in links 31 that are in turn suspended from pins 32 fixed in the ends of valve operating levers 33 and 34. Both of the pins 30 and 32 for each bell are positioned in the slot of the corresponding link 31, and owing to the fact that there is a loose fit between the link 31 and the legs 29, the pin 30 is free to move to a certain extent with respect to the link 31 in a plane at right angles to the link. The bells 27 and 28 thus have substantially universal mountings which is of advantage in enabling them to properly find their seats when the levers 33 and 34 are raised.

The upper end of casing section 14 is offset somewhat to one side as shown in Figs. 1 and 2, and is provided in that part of its extent with two parallel walls 35 and 36 and a connecting wall 37 which is formed like a segment of a cylinder. On the outer sides of the walls 35 and 36, and preferably integral therewith, there are bearing bosses 38 and 39 in which I mount a shaft 40. The latter carries a vane wheel 41 having a series of vanes 42, preferably provided with retaining fingers 43, which delay the dumping of the fuel carried by the vanes and cause the feed of fuel to the chamber above bell 28 to be more or less steady, that is during the actual movement of the wheel. The casing is provided with an inlet 44 which is to be constantly filled with fuel and which is offset from the shaft 40 to an extent such that the angle of

repose of the fuel will always cause the top surface of the fuel to engage the wheel, whereby no fuel can enter the upper bell chamber except that which is delivered to it by the rotation of the wheel.

Actuation of the wheel 41 is accomplished in a step by step movement in the direction of the arrow 45, Fig. 2, by means of a ratchet wheel 46 keyed to the shaft 40, with which engage one or more pawls 47 pivotally mounted upon a plate 48 which has a loose bearing on the shaft 40. A portion only of the ratchet wheel 46 is indicated in Fig. 2. This plate is oscillated back and forth by a link 49 pivoted to the plate at 50. The lower end of link 49 is bifurcated, as shown at 51 in Fig. 3, to straddle a nut 52 to which it is pivotally connected by a pin 53. Nut 52 runs upon a screw 54 which has smooth portions freely rotatable in the ends of a yoke 55 which has a loose bearing upon a shaft 56. The screw 54 may be rotated in its bearings in the yoke 55 by means of a wheel 57 having a crank 58 or any other suitable handle, such rotation serving to move the nut 52 along the screw 54 and thus to vary the throw of the link 49 and consequently the number of teeth in the ratchet wheel 46 over which the pawls 47 move for each return stroke.

Oscillating movement is imparted to yoke 55 by a link 59, 60 pivoted to the yoke at 61. At its lower end this link is pivotally connected to a bifurcated arm 62 by means of a pin 63. The arm 62 is fixed upon a shaft 64 mounted to rock in bearings 65, 66 and 66'. The shaft 64 has a lever arm 67 keyed thereto, through which oscillating motion is imparted to the shaft by a reciprocating rod 68, 69 having a bifurcated end 70 which straddles arm 67 and is pivotally connected thereto by means of pin 71. The rod 68, 69 may be reciprocated by any suitable power means.

Referring now to the means for actuating the valves 27 and 28, these valves, as previously stated, are hung from lever arms 33 and 34, respectively. These arms extend through rectangular openings 72 and 73 in corresponding side walls of the casing sections 13 and 14. The hubs of the levers 33 and 34 are flat sided vertical sectors 74 and 75 which fit fairly closely the sides of the openings 72 and 73. The curved forward faces of these sectors move in close relation always to the top and bottom edges of the openings 72 and 73, and hence fuel is quite effectively prevented from working out through the said openings. The hubs of the lever arms 33 and 34 have squared openings to fit squared portions of a rock shaft 76 and the rock shaft 56 previously referred to.

These two shafts are mounted in projecting portions 77 and 78 of a casting 79 which is machined on its rear face to fit machined surfaces on the casing sections 13 and 14, and is secured in place by screws or the like extend-

ing through holes 80 in the casting and threaded into tapped openings in the casing. Hence, the casting 79 becomes in a sense a part of the casing, preventing the escape of gas by way of the openings 72 and 73 and at the same time constituting a mounting for the various working parts of the apparatus, whereby the mechanism may be assembled conveniently upon the casting 79 and then mounted upon the casing as a unit. Rigidly secured to the shafts 76 and 56 are a pair of weights 81 and 82 of a size sufficient to overbalance the bells 27 and 28, respectively, with their supporting connections, these weights therefore tending always to raise the bells and hold them in closed position.

The casting 79 carries a shaft 83 upon which is fixed a ratchet wheel 84. Upon opposite sides of the latter a pair of pawl carrying plates 85 are mounted to have loose movement upon the shaft 83. These two plates are joined at the bottom by a bolt 86 running through a suitable spacer and at the top by bolts 87 and 88, the first of which forms a pivotal mounting for a pawl 89 and the second of which forms a pivotal mounting for the upper end of an operating link 90 which is pivotally connected at its lower end by a pin 91 to the bifurcated arm 62 previously described. Obviously, reciprocation of the link 90 produces oscillation of the plates 85 which acts through pawl 89 to impart step by step rotation to the shaft 83 in a clockwise direction, as viewed in Fig. 2. On the shaft 83 there is keyed a sleeve 92, integral with which is a cam 93 having one high spot, and a second cam 94 having two low spots, one diametrically opposite the other.

A bifurcated lever 95 is loosely mounted on a shaft 96 supported in brackets on the casting 79. A follower 97 is mounted between the bifurcations of the lever 95 and runs upon the face of the cam 94. The upper end of the lever carries a trunnion 98 in which there is a cross perforation that receives with a sliding fit a pin 99 having an eye 100 surrounding a pin 101 mounted in a crank arm 102 that is integral with a counter-balance weight 103, the latter having a loose bearing on shaft 56. The distance between pin 101 and trunnion 98 is adjustable, a coil spring 104 tending to separate these parts and a nut 105 when turned upon the threaded end of pin 99 tending to bring them together. It will be seen that as the follower 96 moves outwardly and inwardly in response to the movements of cam 94, the lever connections described will cause counter-balance weight 103 to move upwardly and downwardly.

A bifurcated lever 106, very similar in construction to the lever 95, is also journaled on the shaft 96 and carries a follower 107 running on the face of cam 93. The upper end of lever 106 is connected to weight 82 in identi-

cally the same manner as the weight 103 is connected to the lever 95.

On the rear side of the casting 79 is a bracket 108 in which is mounted the pivot 109 of a lever 110 similar to the levers 95 and 106 and carrying a follower 111 which also runs upon the cam 93. The lower or swinging end of the lever 110 is connected through trunnion 112, pin 113, spring 114, adjusting nut 115 and eye 116 to a pin 117 in a crank arm 118 integral with weight 81 which, as previously stated, is fixed to shaft 76.

The levers 33 and 34 are preferably formed with knife edges on the upper sides in order to prevent the lodgment of coal or tar thereon.

The link 59, 60 and the reciprocating rod 68, 69 are made in two parts as shown, so that when a load greater than what may be determined upon as a safe load is impressed upon this link or rod, there may be relative motion between its parts. To this end I mount a shear pin 119 in aligning holes in the two parts of the link 59, 60. The upper end of the part 60 projects into the space between the bifurcations of the part 59 and carries a laterally extending head 120 in which is threaded an adjustable stop 121 which may be locked in any adjusted position by means of a wing nut 122. The stop 121 may be adjusted so as to bear against a projection 123 on the part 59 of the link, whereby any looseness that might result from an inaccurate fit of the shear pin may be taken up. Now, in case the vane wheel 41 should become jammed for any reason on the upward stroke of the link 59, 60, which is the power stroke, the shear pin 119 would be broken and the part 60 would merely move up and down in the part 59, thus preventing any possible damage to the mechanism.

There is a similar shear pin 119 between the parts of the reciprocating rod 68, 69, but as the power stroke of this rod tends to separate the two parts thereof instead of telescoping them together, as in the case of link 59, 60, the means for taking up looseness is arranged oppositely to that above described, that is to say, the adjustable stop 124 is mounted in the head of a pin 125 which is set into the part 69, and the stop 124 is made to bear against a projecting lug 126 on the part 68 of the rod. The power stroke of this rod is indicated by the arrow 127.

In the operation of the apparatus it will be observed that the vane wheel 41 is turned through a certain angle which may be varied by adjustment, during each upward stroke of the links 49 and 59, 60, which corresponds to the inward stroke of the rod 68, 69. On each opposite stroke of these parts the pawls 47 merely ride over the teeth of the ratchet wheel 46. Power is imparted to the shaft 83, however, on the outward stroke of the rod 68, 69, that is the one indicated by the arrow 128.

127. In this way both strokes of the rod 68, 69 are utilized as power strokes, each stroke doing a part of the work required, so that I am enabled to use a lower power supply more evenly distributed.

In following the operation of the valves 27, 28, assume that both valves are closed and that the shaft 83 and its sleeve 92 are in such a position that the lifting side of the cam 93 is just about to engage the follower 107. (See Fig. 4.) Now, the next outward stroke of the rod 68, 69 causes the ratchet wheel 84 to be revolved one tooth. This brings the high spot of cam 93 into engagement with the follower 107 and fully opens the valve 28. At the same time the follower 97 moves from a circular surface of the cam 94 into one of the low spots of the same, thereby lowering the counter-balance weight 103. The wheel 84 has eight teeth. During this one-eighth revolution, the weights 82 and 103 have moved in opposite directions and the descent of weight 103 has helped to lift weight 82. On the next inward stroke of the rod 68, 69 the pawl 89 merely moves backward to engage the next tooth of its ratchet 84. The second forward movement of rod 68, 69 causes cam 93 to move out from under follower 107 enabling weight 82 to raise valve 28 and close the same. On this same stroke the cam 94 is turned sufficiently to carry follower 97 out of the low spot and onto a circular surface of the cam, thereby raising counter-balance weight 103. The movement of the follower 107 down the descent surface of cam 93 gives the weight 82 a leverage which tends to revolve the cam in a forward direction faster than is intended or desired. This tendency is overcome, however, by the fact that the weight 103 must be raised at the same time by the travel of the follower 97 out of its low spot on cam 94. This counter-balancing, or prevention of overrunning, of the valve follower on the upward motion of the valve is a highly important feature of my invention.

On the next two complete reciprocations of the rod 68, 69 all of the followers 97, 107 and 111 travel on circular faces of the two cams, and as a result the valves are not actuated but remain in their closed position.

On the fifth outward stroke, however, the follower 111 is brought onto the high spot of cam 93, thus raising weight 81, lowering valve 27, and the follower 97 moves into a low spot on cam 94 diametrically opposite the spot previously occupied and again lowers weight 103. The valve 27 remains open on the inward stroke of the rod 68, 69 and on the next or sixth outward stroke the follower 111 leaves the high spot of cam 93 and the follower 97 moves out of its low spot thereby moving weights 81 and 103 in opposite or counter-balancing directions and closing the valve 27. On the seventh and eighth strokes

the valves are both idle and the cycle repeats itself beginning with the ninth stroke.

The purpose of the operation above described is well known to those skilled in the art, it being the delivery of small charges of coal step by step from casing section 14 into section 13 and later from that section down into the producer body, without opportunity for a substantial amount of gas to escape from the producer.

It will be noted that with this construction no special ratchet mechanism is required to prevent the overrunning of the cam 93 while either valve is being closed, and that the need for such special ratchet mechanism or equivalent means is wholly avoided by the provision of a counter-weight 103 and its associated parts, including the cam 94 and follower 97.

Owing to the reverse taper form of the lower portion of casing section 11, indicated at 130, the fuel which is discharged by valve 27 and which is deflected outwardly thereby, is stopped and deflected inwardly, so that it descends to the fuel bed evenly through the opening in the producer top instead of in a ring as would be the case were the surface 130 omitted.

While I have described my invention as applied to the fuel feed mechanism of a gas producer, it is not necessarily confined to this particular use, and while I have shown a preferred construction changes may be made in the mechanism employed without departing from the spirit and scope of the invention.

Having thus described my invention I claim:

1. In apparatus for feeding material, a valve in the line of feed, mechanism for operating said valve comprising a cam and a cam follower operatively connected with said valve, a counter-balance weight, and a second cam interconnected with said first cam and mounted to move in timed relation therewith, said second cam being operatively connected with said counter-balance weight and timed to move said counter-balance weight from high to low position and back again while the said follower moves up the ascent side of said cam and down the descent side thereof.

2. In apparatus for feeding material, a pair of valves spaced apart in the line of feed, weights tending to close each of the said valves, mechanism for opening said valves alternately comprising a cam, a counter-balance weight, and a second cam interconnected with said first cam and mounted to move in timed relation therewith, said second cam being adapted to move said counter-balance weight upwardly when either of said valve weights moves downwardly.

3. In apparatus for feeding material, a valve in the line of feed, a weight tending to close said valve, means for opening said valve

in opposition to said weight, said means comprising a cam with a relatively sharp descent surface, and means for preventing the weight from transmitting motion to the cam during engagement with said descent surface, said means comprising a second cam operatively interconnected with said first cam, and a counter-balance weight adapted to be raised by said second cam while the 10 first weight is being lowered by the descent surface of said first cam.

4. In apparatus for feeding material, a valve in the line of feed, a weight tending to close said valve, means for opening said 15 valve in opposition to the force of said weight, said means comprising a cam with a relatively sharp descent surface, and means for preventing the weight from transmitting motion to the cam during engagement with 20 said descent surface, said means comprising a second cam rigid with and movable about the same axis as said first cam, and a counter-balance weight adapted to be raised by said second cam while the first weight is being 25 lowered by the descent surface of said first cam.

5. In apparatus for feeding material, a valve in the line of feed, a movable weight, means for actuating the said valve and 30 weight comprising a pair of interconnected cams one of which has a high spot and the other a low spot, and means for moving said valve from one cam and said weight from the other, said two means being in 35 operative relation with said two spots simultaneously whereby the load of the weight tends to check the closing movement of the valve and assist its opening movement.

6. In apparatus for feeding material, a 40 valve in the line of feed, a movable weight, means for actuating said valve and weight comprising a pair of interconnected cams, each cam having a circular portion and one cam having a high spot and the other a 45 low spot, the angular distance from each spot to the circle of that cam being the same, and means for moving said valve from one cam and said weight from the other, said two means being in operative relation with 50 said two spots simultaneously, whereby the load of the weight tends to check the closing movement of the valve and assist its opening movement.

7. In apparatus for feeding material, a 55 pair of separated valves in the line of feed, a movable weight, means for actuating said valves and weight comprising a pair of interconnected cams, the first cam having a circular portion and a high spot and the second cam having circular portions and two low spots, and means for moving said valves from said first cam and said weight from 60 said second cam, said means being in operative relation with the high spot and one low

spot simultaneously and with the high spot and the other low spot simultaneously.

8. In a device of the class described, two feeders working intermittently, separate ratchet mechanisms for operating said feeders, and a reciprocating element having connections for actuating one of the said ratchet mechanisms when moved in one direction and for actuating the other of said mechanisms when moving in the opposite direction. 70

9. In an apparatus for feeding material, a chamber, a valve adapted to seat in the bottom of the chamber, a horizontal rock shaft located outside said chamber, a rock arm carried by said shaft for actuating said valve extending through an opening in one side wall of said chamber, said arm carrying a member adapted to close said opening in all positions of the arm. 75

10. In a fuel feed for gas producers, a base and a casing spaced apart vertically, a bottom member for the casing having a valve seat therein, said bottom member being interposed between the base and the casing and normally supporting the casing, and means for raising the casing temporarily and supporting it from said base independently of said bottom member, whereby the bottom member may be slid out of position for repair or replacement. 80

11. In a fuel feed for gas producers, a base and a casing spaced apart vertically, a bottom member for the casing having an opening therethrough surrounded by a valve seat, said bottom member being interposed between the base and the casing and normally supporting the casing, a bell-valve adapted to engage said seat when in its uppermost position, operating means for said valve attached to the same from above, said means being disconnectible, and means for raising the casing temporarily and supporting it from said base independently of said bottom member, whereby the bottom member may be slid out of position for repair or replacement. 85

12. In apparatus for feeding material, a valve in the line of feed, a cam for actuating said valve, a ratchet connection for rotating said cam, a follower for said cam connected with said valve, and means for impressing a reverse torque upon said cam as said follower travels down the descent side of the cam, whereby overrunning of the cam is prevented. 90

13. In apparatus for feeding material, a valve in the line of feed, means tending to close said valve, a cam and follower for opening said valve in opposition to said means, a ratchet connection for rotating said cam and means for applying a rotating force to the cam to prevent the follower from causing the cam to overrun while the valve is being closed. 95

14. In apparatus for feeding material, a valve in the line of feed, a counter-weight 100

tending to close said valve, means comprising a cam and a follower for opening the valve and elevating the counter-weight, a ratchet connection for rotating said cam and means for applying a turning force to the cam or its shaft to restrain the movement of the counter-weight in closing the valve.

15. In a feed mechanism, a valve, a seat therefor, a counter-weight connected to the valve tending to hold the same against its seat, a balancing counter-weight, and a pair of interconnected cams, one serving to raise said valve weight so as to open the valve and serving to permit the lowering of the weight to close the valve, said second cam serving to permit the balancing counter-weight to be lowered while the valve weight is being elevated and to elevate the balancing counter-weight while the valve weight is descending.

20. 16. In a fuel feed for gas producers, a casting built in two superposed sections, a valve-seat member interposed between said sections and normally bearing the weight of the upper section, said sections having superposed portions extending laterally beyond said valve-seat member, said portions being adapted to receive means for spreading the sections.

25. 17. In a fuel feed for gas producers, a casting built in two superposed sections, a valve-seat member interposed between said sections and normally bearing the weight of the upper section, said sections having superposed portions extending laterally beyond said valve-seat member and a relieving screw threaded into one of said portions and adapted to bear upon the other.

30. 18. In a fuel feed for gas producers, a base and a casing spaced apart vertically, a bottom member for the casing interposed between the base and the casing and normally supporting the casing, and screws associated with said base and casing outside of said bottom member for raising and supporting the casing independently of the bottom member, whereby the bottom member may be slid out of position for repair or replacement.

45. In testimony whereof, I hereunto affix my signature.

JOHN F. ROGERS.
